Fig. 2.

A technical drawing of a mechanical device. At the top is a circular plate 5 with a central vertical rod 14. Below this is a horizontal beam 16. A curved rod 15 is attached to the beam 16. A vertical rod 10 is attached to the beam 16. A horizontal beam 12 is attached to the vertical rod 10. A vertical rod 18 is attached to the horizontal beam 12. A vertical rod 19 is attached to the horizontal beam 12. A vertical rod 21 is attached to the horizontal beam 12. A vertical rod 23 is attached to the horizontal beam 12. A vertical rod 24 is attached to the horizontal beam 12. A vertical rod 25 is attached to the horizontal beam 12. A vertical rod 8 is attached to the horizontal beam 12. A vertical rod 3 is attached to the horizontal beam 12. A vertical rod 9 is attached to the horizontal beam 12. A vertical rod 1 is attached to the horizontal beam 12. A vertical rod 2 is attached to the horizontal beam 12.

WITNESS:

UNITED STATES PATENT OFFICE.

EDWARD JAMES SCHRAMKE, OF SAGINAW, MICHIGAN.

VEHICLE.

Application filed July 12, 1922. Serial No. 574,561.

To all whom it may concern:

Be it known that I, EDWARD J. SCHRAMKE, a citizen of the United States, residing at Saginaw, West Side, in the county of Saginaw and State of Michigan, have invented new and useful Improvements in Vehicles, of which the following is a specification.

My present invention has reference to improvements in vehicle toys of the type for use and amusement of children, and relates particularly to a device of this character having a platform supported on wheels and provided with means for propelling the vehicle upon the alternate downward movements transversely of the platform by the occupant on the platform.

A further object is to produce a toy of this class which may be readily guided as well as propelled by the occupant thereof, and wherein the propelling of the toy will impart healthy exercise as well as amusement to the occupant.

The foregoing, and other objects which will present themselves as the nature of the invention is better understood, may be accomplished by a construction, combination and operative association of parts such as is disclosed by the drawings which accompany and which form part of this application.

In the drawings—

Figure 1 is a side elevation of the improvement.

Figure 2 is a rear elevation thereof.

Figure 3 is a top plan view thereof.

Figure 4 is a sectional view on the line 4—4 of Figure 3.

Figure 5 is a sectional view on the line 5—5 of Figure 3.

The steering wheel of the vehicle is indicated by the numeral 1 and the propelling wheels by the numeral 2. The steering wheel has its shaft journaled in suitable bearings in the forked end 3 of a steering post, the said post being journaled in a steering column 4 and having its end outward of the column provided with a steering wheel 5.

The steering column 4 is provided with a pair of spaced downwardly arched brackets 6 and 7 respectively, the bracket 6 being formed with one end of the longitudinally arranged frame member 8 of the vehicle, the bracket 7 having an offset end which is secured to the frame member at its juncture with the arched end thereof which I have termed the bracket 6.

The frame member 8 is in the nature of a board and has its under face, adjacent its outer end provided with bearing members 9 for the axle 10 of the propelling wheel 2. The member 8 is provided with a transversely arranged cleat 11 supported at an elevation above the said member by suitable blocks 12. The cleat centrally supports one end of a rod or shaft 13, the second end of the rod or shaft being supported in the bracket 7. There is also a spacing and reinforcing element 14 between the brackets 6 and 7.

The top or platform of the toy is indicated by the numeral 15, the same having at its rear end a depending bolster 16 provided with a central opening through which the rod or shaft 13 passes. At its forward end the platform 15 is centrally provided with a depending plate or bracket 17 through which the rod or shaft passes, the plate or bracket 17 being in slight contacting engagement with the bracket 7.

The propelling wheels 2 are loose on the shaft 10, the inner ends of the hubs of the said wheels contacting with the bearing members 9, and the outer ends or bases of the hubs being provided with ratchet wheels 18. On the outer ends of the shafts 10 there are keyed cranks 19. The cranks are preferably in the nature of flat plates and are centrally connected to the axle. The cranks have pivotally secured on their inner faces preferably spring influenced dogs 20 which are designed to engage with the ratchet wheels on the propelling wheels 2. Pivotally connected to the cranks 19 are links 23. The links are also pivotally connected to arms 24. The arms 24 are disposed at an outward angle with respect to the platform 15, the said arms being in the nature of metal plates offset at 25 from the portions 26 thereof which are secured to the sides of the platform.

In practice, the operator stands on the platform and grasps the steering wheel 5. The operator exerts alternate pressure on the platform at the sides thereof opposite the shaft 13 so that a continuous tilting movement of the platform transversely with respect to the longitudinal plane thereof is imparted thereto, and such movement of the platform will influence the links 23 to cause the pawls on the cranks to engage the teeth of the ratchet wheels on the propelling wheels 2, and thus turn the propelling wheels. The

pawl and ratchet wheel engagement between the cranks and the propelling wheels permit the vehicle coasting. The vehicle is guided by turning the steering wheel 5, and it is thought that the foregoing description, when taken in connection with the drawings will fully set forth the construction and operation of the improvement to those skilled in the art to which this invention relates.

- 10 Having described the invention, I claim:—
1. In a toy vehicle, a steering wheel and propelling wheels, a steering post having a forked end in which the steering wheel is journaled, a column for the post and an operating wheel for the post, downwardly inclined brackets secured to the column and to each other, a frame member on the lower bracket, a shaft for the drive wheels, bearings on the frame member for the shaft, a cleat supported on the frame member, a shaft centrally secured to the cleat and one of the brackets, a platform having a bolster on its rear end receiving the last mentioned shaft therethrough and having a bracket on its forward end also receiving the shaft therethrough, cranks on the propelling wheel shaft, links connected with the crank, and arms having offset ends secured to the sides

of the platform and connected to the links, as and for the purpose set forth. 30

2. In a toy vehicle, a steering wheel and propelling wheels, a shaft for the propelling wheels and on which the latter are freely journaled, a steering post having a forked end in which the steering wheel is journaled, 35 a column for the post and an operating wheel for the post, downwardly inclined brackets secured to the column and to each other, a frame member on the lower bracket having bearings for the propelling wheel shaft, a 40 cleat supported above the frame above said shaft, a shaft secured in the cleat and the upper bracket, a platform having its forward end pivotally secured to the last mentioned shaft and having a bolster on its rear end 45 which receives the last mentioned shaft therethrough, arms having offset outer ends secured to the sides of the platform, cranks on the ends of the propelling wheel shaft, links connecting the shafts with the arms, spring 50 influenced pawls on the cranks, and ratchet wheels on the propelling wheel shaft for engagement by the pawls, as and for the purpose set forth.

In testimony whereof I affix my signature.
EDWARD JAMES SCHRAMKE.
